US00D995426S

(12) **United States Design Patent** (10) Patent No.: **US D995,426 S**
(45) Date of Patent: **** Aug. 15, 2023**

(54) **POWER ADAPTER**

- (71) Applicant: **Lenovo (Singapore) Pte. Ltd.**,
Singapore (SG)
- (72) Inventors: **Seiji Morioka**, Yokohama (JP); **Kazuo Nakada**, Yokohama (JP); **Yoshihito Nakagaki**, Yokohama (JP)
- (73) Assignee: **Lenovo (Singapore) Pte. Ltd.**,
Singapore (SG)
- (**) Term: **15 Years**
- (21) Appl. No.: **29/737,794**
- (22) Filed: **Jun. 11, 2020**

(30) **Foreign Application Priority Data**

- Dec. 11, 2019 (JP) D2019-027463

(57) **CLAIM**

The ornamental design for a power adapter, as shown and described.

DESCRIPTION

FIG. 1 is a perspective view of a power adapter showing our design;

FIG. 2 is a perspective view thereof;

FIG. 3 is a side view thereof;

FIG. 4 is a side view thereof;

FIG. 5 is an end view thereof;

FIG. 6 is an end view thereof;

FIG. 7 is a top view thereof;

FIG. 8 is a bottom view thereof; and,

FIG. 9 is a cross-sectional view thereof.

The broken lines in the drawings illustrate portions of the power adapter or environment and form no part of the claimed design.

1 Claim, 9 Drawing Sheets
